United States Patent Office

Des. 227,470
Patented June 26, 1973

227,470

DENTAL MIRROR STRUCTURE

James Vannes Boone, Meadows Bldg.,
Dallas, Tex. 75206

Filed July 17, 1972, Ser. No. 272,445

Term of patent 14 years

Int. Cl. D24—02
U.S. Cl. D24—1 D

FIG. 1

FIG. 2

FIG. 3

FIG. 4

FIG. 1 is a perspective view of the dental mirror structure showing my new design;

FIG. 2 is a side view of the device of FIG. 1;

FIG. 3 is an end view of the device of FIGS. 1 and 2;

FIG. 4 is a front elevational view, showing the adjustable mirror at one positional setting.

I claim:

The ornamental design of a dental mirror structure, as shown and described.
